UNITED STATES PATENT OFFICE.

JOHN H. LEHMAN, OF ELKHART, INDIANA; BESSIE A. LEHMAN ADMINISTRATRIX OF
SAID JOHN H. LEHMAN, DECEASED.

TRAFFIC-INDICATOR.

1,374,380.

Specification of Letters Patent. Patented Apr. 12, 1921.

Application filed December 22, 1919. Serial No. 346,511.

To all whom it may concern:

Be it known that I, JOHN H. LEHMAN, a citizen of the United States, residing in the city of Elkhart, county of Elkhart, Indiana, have invented certain new and useful Improvements in Traffic-Indicators, of which the following is a specification.

This invention relates to traffic indicators, and more especially to illuminated indicators of the character mentioned and described, and adapted to be placed at street intersections.

An object of my invention is the production of an illuminated traffic indicator for the center of street intersections which is simple, effective, cheap and easily installed. Another object is the production of a traffic indicator of the character described in which improved drainage means is provided. A third object is the production of a traffic indicator having improved facilities for inserting or removing the lamps thereof. Other objects of my invention are mentioned and described herein.

The preferred embodiment of my invention is illustrated in the accompanying drawing in which Figure 1 illustrates my invention when placed at the center of a street intersection; Fig. 2 is a vertical section through the indicator device as a whole; and Fig. 3 is an exterior view in end elevation.

Similar numerals of reference indicate like members throughout the several views on the drawing.

Referring to the drawing in detail the numeral 1 indicates a base plate, preferably of cast metal, adapted to be embedded in the street in concrete or cement, and provided with the substantially funnel-form central structure 2 in which the opening 3 is formed and adapted to drain any moisture accumulation from the upper surface of said plate. The under side of the base plate 1 may be provided with a plurality of downwardly extending and radially arranged ribs 4, 4 which may extend from the funnel mouth 3 outward toward the outer periphery of the base plate and which are adapted to be embedded in the cement or concrete in which the plate is laid to effect a rigid and permanent connection between the plate and concrete.

The numeral 5 illustrates the indicator body member which is preferably domed and somewhat oval in general configuration

and which may be secured to the base plate 1 by bolts 6, 6. The member 5 may be provided with a plurality of openings 7, 7 in which glass plates 8, 8 are rigidly mounted in any suitable manner and preferably depressed below the outer face of the body member 5 to avoid breakage of said plates by vehicle wheels. The member 5 may be provided with a hand hole 9 in its top medial portion which opening is adapted to be 60 closed normally by a flanged cover 10 removably fastened in or over said opening by suitable screws 11, 11, said hand hole cover being provided with the lateral flange 12 which engages in the lateral recess 13 surrounding the opening 9 whereby the outer periphery or face of said plate 10 is brought substantially flush with the outer face of the member 5.

The cover 10 may be centrally apertured 75 at 14 in which aperture the glass plate 15 may be rigidly secured and depressed similar to the plates 8, 8 and for the same purpose. The interior of the indicator may carry a plurality of incandescent lamps 16 80 and 17 supported upon a socket member 18 which may be removably mounted upon a prong 19 of the carrier member 20 which may be rigidly secured to the base plate 1 by screws 21, 21.

A conduit wire 22 may connect the lamps 16 and 17 with any suitable source of electric current. The carrier 20 is preferably made of bar metal to permit of the flow of water to the opening 3 which preferably 90 communicates with the earth direct to enable the ready absorption of any such moisture which may accumulate within the indicator. When the lamps 16 and 17 are worn out or damaged in any manner ready access thereto is gained by the removal of the hand-hole cover 10, and the lamp socket 18 may be withdrawn to the exterior of the cover 5 to install new lamps therein, whereby the necessity for the removal of the 95 domed cover 5 is eliminated and lamp replenishment much simplified.

I claim:

1. In a traffic indicator, a hollow body member provided with a domed top portion, said domed top being provided with a plurality of windows and an opening adapted to serve as a hand-hole, said opening being relatively smaller than said domed top, said body being provided also with an 105 110

opening in its bottom wall adapted for draining moisture from the interior of said body member; a hand-hole cover plate; means connecting the cover plate with the 5 domed top for detachably securing the former to the latter; and a light mounted within said body member.

2. A traffic indicator comprising a base plate of substantially funnel-form structure, 10 the bottom whereof is provided with a plurality of projections adapted to be embedded

in concrete for rigidly retaining said plate in position; a domed cover member fastened to said base plate, said cover being provided with a plurality of windows; and an 15 electric light mounted beneath said domed cover.

In testimony whereof I have hereunto affixed my signature this 18th day of December, 1919.

JOHN H. LEHMAN.
